UNITED STATES PATENT OFFICE.

CHARLES F. HOOFER, OF SPOKANE, WASHINGTON.

FLANGE-OILER.

1,054,550.

Specification of Letters Patent. Patented Feb. 25, 1913.

Application filed March 5, 1912. Serial No. 681,772.

To all whom it may concern:

Be it known that I, CHARLES F. HOOFER, a citizen of the United States, and a resident of Spokane, in the county of Spokane and State of Washington, have made certain new and useful Improvements in Flange-Oilers, of which the following is a specification.

My invention relates to improvements in devices for lubricating flanges of locomotives and other track vehicles, and it consists in the constructions, combinations, and arrangements herein described and claimed.

An object of my invention is to provide means whereby the flanges of locomotives or other vehicles may be oiled automatically at certain places where such lubrication is most necessary, such as on curves in the track.

Other objects of my invention are to provide automatic means operated by air pressure for positively feeding the lubricating fluid to the flanges of the wheels.

A further object of my invention is to provide a novel form of oil container.

A further object of my invention is to provide a novel form of oil distributor.

Other objects and advantages will appear in the following specification, and the novel features of the device will be particularly pointed out in the appended claims.

My invention is illustrated in the accompanying drawings forming part of this application in which—

Figure 1 is a side view of a locomotive showing my invention as applied thereto, Fig. 2 is a central section through one of the oil retainers, Fig. 3 is a front view of an oil retainer, Fig. 4 is a detail perspective view of a portion of the oil feed valve, Fig. 5 is a section through the air control valve, showing the latter in its closed position, Fig. 6 is a side view of the air control valve, Fig. 7 is a section through the air control valve showing the valve in its open position, Fig. 8 is a section along the line 8—8 of Fig. 5, Fig. 9 is a detail view showing the oil distributing device, Fig. 10 is a front view of a portion of the oil distributing device, showing the means for

suspending the latter, Fig. 11 is a sectional view of a portion of the distributing device, Fig. 12 is a detail view showing the position of a spring retaining pin before locking, and Fig. 13 a view similar to Fig. 12, showing the position of the spring pin when locked.

In carrying out my invention I provide oil receptacles or retainers like that shown at A in Figs. 1 and 2. I may also use double retainers like that shown at B in Fig. 1, these being the same as the retainers A except that they are larger, and are adapted to carry two or more oil feeding mechanisms in communication with the same receptacle. The retainers may be made of any suitable material, but are preferably of cast brass or iron. They consist of an attaching plate 1 which forms one wall of the retainer having a bottom 2 and a top 3 provided with a hinged cover 4. The bottom 2 slopes downwardly to a drain passage 5, which is normally closed by a plug 6. At the top of the retainer or receptacle just underneath the cover 4 is a screen 7 for straining the oil. This may be lifted out and cleaned of the dirt or refuse. Each receptacle is provided with one or more cylinders 8 which pass through openings in the cover 3. The cylinder is threaded as shown at 9, and is screwed into an opening in the bottom 2. The top of the cylinder 8 is threaded as shown at 10 to receive a screw union 11 which secures a pipe 12 to the cylinder 8, a suitable gasket 13 being provided. The bottom of the cylinder 8 is provided with openings 14 communicating with the interior of the receptacle. Below the openings 14 is a valve seat 15, while at the end of the cylinder is another valve seat 16.

The bottom 2 is provided with a downwardly projecting integral nipple 17 which is threaded to receive a union 18 for connecting the nipple 19, as clearly shown in Fig. 2.

Within the cylinder 8 is an elongated valve 20, which is provided with packing rings 21 at one end. This valve has a passage 22 extending very nearly through it, a similar passage 23 connecting the passage 22 with the space 24 above the valve 20. Referring

now to Fig. 4, it will be seen that the valve 20 is provided with an enlarged portion 20^x having radial guide members 20^y arranged to contact with the inner walls of the cylinder 8. The lower part of the enlarged portion 20^x of the valve is tapered to form a valve face 20^z. On the lower end of a reduced portion 20^y of the valve 20 is screwed a valve member 26, which is arranged to bear against the valve seat 16, a spring 27 being disposed between the valve 26 and the nipple 19, as shown in the drawing.

The air control valve is best shown in Figs. 5 to 8. It consists of a valve casing 28 having an inlet 29 and an outlet 30. In the bottom of the valve casing 28 is a screw plug 31. A valve 32, such as that shown in Figs. 5 and 7 is arranged to bear against a valve seat 33. This valve 32 is provided with radial guide members 32^x which are arranged to engage the interior of the walls of the valve casing 28 as clearly shown in Fig. 8. A stem 34 extends upwardly through a packing gland 35, and terminates just below the end 36 of a bell-crank lever, which is pivoted at 37 to the arms 38 carried by the plate 39 which bears the valve casing 28. A spring 40 bears at one end upon the bottom of the valve 32 and at the other upon the screw plug 31.

In Figs. 9 to 13 inclusive I have shown the oil distributing device. This consists of a bracket 41 having an integral U-shaped yoke 42. Carried in openings 42^a in the arms of the yoke 42 is a cylinder 43 provided with a head 44. The lower end of the cylinder 43 is cut away at the front and rear sides, as shown at 43^a (see Fig. 9) to provide a pair of downwardly extending integral arms 43^b (see Fig. 10). Each of these arms is slotted in the manner shown at 43^c in Fig. 11.

At 45 I have shown a tapering member which is secured to the cylinder 43 in the following manner: As will be seen from Figs. 11, 12 and 13, the tapering member 45 is provided with inwardly extending lugs such as those shown at 46, these lugs being of such a shape that they are permitted to enter the smaller portion of the slot 43^c only when the member 45 and the cylinder 43 are in alinement, but to assume a position like that shown in Fig. 11 when these members are not in alinement so that the lug 46 will engage shoulders like that shown at 47 to prevent the detachment of the tapering member 45. The means for holding the tapering member 45 in its angular relation with respect to the cylinder 43 consists of a spring 48 whose central portion is passed around the lower end of the cylinder, the portions of the spring on each side of the

center being wound around the respective lugs 49 on the outside of the member 45 and the ends of the spring 48 being passed under the respective lugs 50. It will be seen that the tapered member 45 will be held in its angular relation to the center 43 by this spring.

A flexible member 51 such as a hose passes through the cap or head 44, and the cylinder 43 and extends down to the lower end of the tapered member 45, the hose or tube being bent at the joint between the member 45 and the cylinder 43. In order to hold the flexible member or hose in place, I make use of the bent spring 52 whose central portion 52^a is secured in the upper end of the member 45 and whose end portions 52^b are adapted to enter a slot 53 in the member 45 as clearly shown in Figs. 12 and 13. A spring 55 is disposed between the arms of the yoke 42, one end of the spring bearing upon the yoke and the other being secured to the cylinder 43. This will permit the cylinder to turn in one direction under spring tension but will prevent an up and down movement.

Referring now to Fig. 1, I have shown a locomotive which I have denoted in general by L. The locomotive is provided with the usual air reservoir R which communicates by means of the pipe 56 with the inlet 29. (See Fig. 5). The outlet 30 communicates by means of a short pipe 57 with a pipe 58 leading to the pipes 12, 12^a and 12^b, the former entering the reservoir or oil container A and the two latter entering the reservoir or oil container B. A hose or tube like that shown at 51 connects the outlet 19 (see Fig. 2) of each of the oil containers with the oil distributing device 45 which is held in position for delivering oil to the flanges of the wheels W, W^a and W^b respectively, as clearly shown in Fig. 1.

The guide trucks T are connected by means of the rod 60 with a turn buckle 62, the latter being connected in turn by the rod 61 to the lever 36.

From the foregoing description of the various parts of the device the operation thereof may be readily understood. The lubricating fluid is placed in the retainers, being strained through the screen 7. Normally the valve 20 is held in upright position like that shown in Fig. 2, thereby allowing the oil to pass through the openings 14 around the reduced portion of the valve 20. It will not pass the valve member 26 because the latter is against the seat 16. Now when the engine is rounding a curve, the trucks T will be turned so as to pull on the lever 36 through the medium of the rods 60 and 61, thereby causing the inner end of the lever 36 to depress the valve stem

34. The valve 32 will thereupon be moved into the position shown in Fig. 7, against the tension of the spring 40, thus permitting the air to pass up around the valve 32 and through the outlet 30, through the pipes 57 and 58 into the pipes 12, 12^a and 12^b. As stated before, the interior of the oil retainers is similar to that shown in Fig. 2. Consider now the action of the air. As it 10 enters the cylinder 8 it will press downwardly on the head of the valve 20, driving the same before it so as to open valve 26 and bring the face 20^a into contact with the valve seat 15. The oil which has already 15 been admitted through the openings 14 will be permitted to pass into the flexible tubes 51. Moreover, the air pressure passing through the passages 22 and 23 in the valve member 20 will cause the oil to be blown 20 out upon the flanges of the wheels. In the meantime, the movement of the valve 20 has shut off the flow of oil so that only a small portion is forced out. This is sufficient, however, to lubricate the flange for the time 25 being. Now when the straight portion of the track is reached and the truck returns again to its normal position the lever 36 will be lifted and the spring 40 will restore the valve 20 to the normal position, thereby 30 cutting off the air from the cylinder 8. The air of course will continue to pass through the passages 22 and 23 until the normal pressure inside of the cylinder 8 is attained when the member 20 will be pushed upwardly 35 into its initial position, thereby reseating valve 26 and permitting another flow of oil through the openings 14 preparatory to the next lubricating portion.

I am aware that other forms of the device 40 based upon the same general plan might be made but I consider as my own all such modifications as fairly fall within the spirit and scope of the invention.

I claim:

- 45 1. In a device for lubricating flanges of vehicle wheels, the combination of a source of motive fluid, an oil retainer, a motive fluid control mechanism disposed between the source of motive fluid and the oil retainer, connections between said source and said control device on one side and by said control device and said oil retainer on the other side, an oil distributing device, flexible connections between said oil retainer and said oil distributing device, an oil feed mechanism carried by said oil retainer adapted to be operated by motive fluid, and automatic means for operating said fluid controlling device.
- 50 2. In a device for lubricating flanges of vehicle wheels, the combination of a source of motive fluid, an oil retainer, a motive fluid control mechanism disposed be-

tween the source of motive fluid and the oil retainer, connections between said source and said control device on one side and by said control device and said oil retainer on the other side, an oil distributing device, flexible connections between said oil retainer and said oil distributing device, an oil feed mechanism carried by said oil retainer adapted to be operated by motive fluid, automatic means for operating said fluid controlling device, said automatic means comprising a lever arranged to operate said fluid control mechanism, and means attached to the trucks of the vehicle for actuating said lever.

3. In a device for lubricating flanges of vehicle wheels, an oil retainer, a bracket secured to the frame of the vehicle, a pipe carried by said bracket, an oil distributing device hinged to said pipe, and a flexible connection between said oil retainer and the discharge end of said oil distributing device, said flexible connection passing through said pipe.

4. In a device for lubricating flanges of vehicle wheels, an oil retainer, a bracket secured to the frame of the vehicle, a pipe carried by said bracket, an oil distributing device hinged to said pipe, a flexible connection between said oil retainer and the discharge end of said oil distributing device, said flexible connection passing through said pipe, and means for maintaining said hinged oil distributing device in contact with a wheel.

5. The combination with a source of compressed air, of an oil retainer, an air controlling device disposed between said oil retainer and said source of compressed air, said oil retainer comprising a main reservoir, a tube extending therethrough and provided with openings at its bottom communicating with the interior of the reservoir, a movable valve member within said tube, said valve member having a restricted passage extending longitudinally through the valve and being provided with a pair of valve faces, a connecting pipe between the air controlling means and the restricted passage in said valve member, and a spring for holding one of said valve faces normally against its side and the other away from its seat.

6. In an oil retainer, a main reservoir, a tube extending therethrough and provided with openings at its bottom communicating with the interior of the reservoir, a movable valve member within said tube, said valve member having a pair of valve faces, and a spring for holding one of said valve faces normally against its seat, and the other away from the seat, the movement of one of said valve members from its seat serving to permit a flow of lubricat-

ing fluid out of the reservoir around the valve member and the movement of the other valve from the seat serving to permit the flow of the fluid from the space around the valve member, said valve member being provided with a plunger head at one end and having a central passage extending through

5

said plunger head to the opposite end of the valve member.

CHARLES F. HOOFER.
